(57) CLAIM

The ornamental design for a table, as shown and described.

DESCRIPTION

FIG. 1 is a top, rear, left perspective view of the claimed design for a table;

FIG. 2 is a rear view thereof;

FIG. 3 is a front view thereof;

FIG. 4 is a right view thereof;

FIG. 5 is a left view thereof;

FIG. 6 is a top view thereof;

FIG. 7 is a bottom view thereof;

FIG. 8 is a bottom, rear, left perspective view thereof;

FIG. 9 is an exploded top, rear, left perspective view thereof, wherein exemplary additional unclaimed subject matter is shown; and,

FIG. 10 is a cross-section view of FIG. 2, taken along section lines 10-10 shown in FIG. 2.

The broken lines immediately adjacent to the shaded area depict boundaries of the claimed design and form no part thereof. The broken lines showing the remainder of the table depict environmental structure and form no part of the claimed design.
